UNITED STATES PATENT OFFICE.

RAYMOND G. MOORE, OF BRIDGEPORT, CONNECTICUT, ASSIGNOR TO THE BASSICK COMPANY, OF BRIDGEPORT, CONNECTICUT.

LATCH.

Application filed May 8, 1926. Serial No. 107,542.

The present invention relates to an improved automobile door latch, and has for an object to provide a latch of this character, having both an inside and an outside operating handle, and in which the outside handle may be rendered ineffective in its operation by means controlled from the inside. The latch is especially adapted for use upon doors of closed cars, being applied to all but 10 one of the doors, and which latter is adapted to be locked from the outside.

Heretofore it has been the practice to lock the outside handle, or the latch bolt, against movement, either through manipulation of 15 the inside handle, or through separate inside locking means, so that by exerting a sufficient force upon the locked outside handle the locking means could be forced or broken, and the latch bolt retracted to open 20 the door. It is proposed, in the present embodiment of the invention, to render operation of the outside handle ineffective to operate the bolt, without locking it against turning, however, and which cannot be forced 25 to effect retraction of the bolt. A further object is to provide a latch in which the outside handle is rendered ineffective through a movement of the inside handle in reverse direction to the normal retracting movement, so that in order to restore the operative 30 relation of the inside handle, it is only necessary to move the inside handle in its normal retracting direction.

Another object is to provide a latch construction in which the inside handle mechanism is adapted to operate directly with the bolt independently of the outside retracting means, while the outside handle mechanism operates upon the bolt through an intermediate member.

It is particularly proposed, in the present embodiment, to provide a latch including a latch bolt having a retracting element normally engaged with the outside handle roll-back, and which is adapted to be disengaged 45 therefrom through manipulation of the inside handle to render operation of the outside handle ineffective.

With the above and other objects in view, 50 an embodiment of the invention is shown in the accompanying drawings, and this embodiment will be hereinafter more fully described with reference thereto, and the invention will be finally pointed out in the claims.

In the drawings:

Fig. 1 is a plan elevation of an automobile door latch, according to the present embodiment of the invention, and showing the same in its normal operative relation; 60

Fig. 2 is a transverse sectional view, taken along the line 2—2 of Fig. 1;

Fig. 3 is a longitudinal sectional view, taken along the line 3—3 of Fig. 1;

Fig. 4 is a plan elevation, with the cover plate removed, and showing the parts in the relation in which operation of the outside handle is rendered ineffective; 65

Fig. 5 is a transverse sectional view, taken along the line 5—5 of Fig. 4; and 70

Fig. 6 is a perspective view of the outside handle retracting element employed.

Similar reference characters indicate corresponding parts throughout the several figures of the drawings. 75

Referring to the drawings, the embodiment of the invention shown therein comprises a sheet metal frame or base plate 10 having a face flange 11 bent therefrom at one end, in which a rectangular opening 12 is provided, a lip flange portion 13 of the metal cut from the opening being bent inwardly in parallel spaced relation to the plate 10 to form a bearing for the latch bolt.

The latch bolt 14 is slidably engaged at its relatively thick nose portion 15 in the opening 12 and near its inner end is engaged by guide flanges 16 and 17 struck up from the plate 10, and adapted to guide the bolt in its longitudinal movement, a coil spring 18 being engaged with the inner end of said bolt and normally pressing it to its projected position. 90

The bolt is retained against displacement by means of a flat cover plate 19, flanged at its upper and lower edges, as at 20, and secured to the plate 10 by lugs 21 inserted through slots 22 in the plate 10 and bent over upon the outer surface of said plate. 95

The latch bolt has formed upon its outer surface a pair of transverse ribs 23 and 24, the rib 23 being spaced with relation to the inner surface of the nose 15, and the rib 24 being spaced with relation to the inner end of the bolt, and being respectively engaged 100 in slot openings 25 and 26 in the cover plate 19.

The inside handle roll-back 27 is adapted to engage directly with the rib 24, its hub 28 being rotatably supported in apertures in 110

the plates 10 and 19, and being movable in counter-clockwise direction to retract the bolt.

The outside handle roll-back 29 has its hub 30 rotatably supported in apertures in the plates 10 and 19, and normally engages the upper end portion 31 of an intermediate gate member 32 hingedly connected at its lower end to the latch bolt, being provided for this purpose with bent hinge forming ears 33 and 34 engaged about a shaft 35 secured at its ends in the inner end of the nose portion 15 and in the rib 23 of the bolt, respectively, a spring 35 coiled about said shaft 15 having one end bearing upon said gate member and yieldingly pressing its end 31 into engagement with the plate 10, said end being bent into offset relation, whereby it engages flatly upon said plate. The gate member 20 is provided with a substantially semi-circular cut-out portion 36 at its forward edge, which embraces the hub of the roll-back 29. In the normal operative relation of the parts, the outside handle roll-back 29 engages the 25 end 31 of the gate member, and thereby operates to retract the bolt, as shown in dotted lines in Fig. 1.

In order to render operation of the outside handle ineffective, through manipulation 30 of the inside handle, there is provided, intermediate the gate member and the inside handle roll-back, a bell-crank lever 37 pivotally mounted upon the plate 10 by means of a rivet stud 38. The long arm of 35 this lever extends at its forward end above the upper end of the gate member, and is provided with a knife-edge camming portion 39 adapted upon depression of the lever to enter beneath the end portion 31 of the 40 gate member to thereby raise it away from the surface of the plate 10 to a point where the outer handle roll-back will move beneath said portion, as shown in Fig. 4. A bevel edge portion 40 provided on the portion 31 45 facilitates engagement of the lever end therewith. The short arm 41 of the lever is connected at its lower end by a helical spring 42 to a lug 43 provided on the hub of the outer handle roll-back, and has the double 50 function of yieldingly maintaining the outside handle roll-back in its normal position in contact with the flange 11, and of tending to rotate the lever in clockwise direction, that is, to disengage the same from the gate 55 member.

A lug 44 is bent from the lever and engages the periphery of the inside handle roll-back 27 at a point between the circumferential surface 45 at one side and a cam rise 60 surface 46 at the other side, a notch 47 being provided adjacent said surface 46.

The operation is as follows:

As shown in Fig. 1, in which the parts are in their normal operative relation, the 65 latch bolt is retracted from the inside by the

inside handle, the roll-back 27 being rotated in counter-clockwise direction, and bearing directly upon the flange or rib 24 of the bolt. It is retracted from the outside by the outside handle, the roll-back 29 being rotated in clockwise direction, and through pressure upon the gate member 32, as shown in dotted lines, Fig. 1, retracting the bolt. 70

In order to render operation of the outside handle ineffective to retract the bolt, 75 the inside handle is moved through a partial rotation in opposite direction to its normal retracting movement, (Fig. 4) bringing the cam portion 46 into engagement with the lug 44 and thereby rotating the lever 37 to 80 bring its forward end beneath the upper end of the gate member, the latter being thus moved out of operative relation with the outside handle roll-back 29, this relation being yieldably maintained, as shown in Fig. 4, 85 through engagement of the lug 44 in the notch 47. Upon actuation of the outside handle in this relation, the roll-back 29 moves beneath the gate member, and such actuation is therefore ineffectual to retract 90 the bolt.

The normal operative relation of the outside handle is restored upon moving the inside handle in retracting direction, the initial movement disengaging the lever 37 from the 95 gate member, which moves under the action of its spring into operative relation with the outside handle roll-back, and the continued movement causing retraction of the bolt. 100

Under all conditions the latch bolt is free to be retracted independently of the handles, that is, by pressure directly applied at its nose, as in slamming the door closed.

I have illustrated and described a pre- 105 ferred and satisfactory embodiment of the invention, but it will be obvious that changes may be made therein, within the spirit and scope thereof, as defined in the appended claims. 110

Having thus described my invention, what I claim and desire to secure by Letters Patent is:—

1. In a latch, a latch bolt, retracting means for said bolt including inside and outside 115 manually operable means, a retracting member interposed between said outside retracting means and the bolt and connected to said bolt, and means associated with said inside retracting means adapted upon manipulation of the latter in a non-bolt-retracting direction to remove said retracting member from operative relation with said outside retracting means. 120

2. In a latch, a latch bolt, retracting means for said bolt including inside and outside 125 manually operable means, a retracting member interposed between said outside retracting means and the bolt and connected for longitudinal movement with said bolt, and

- means associated with said inside retracting means adapted upon manipulation of the latter in a non-bolt-retracting direction to remove said retracting member from operative relation with said outside retracting means.
3. In a latch, a latch bolt, retracting means for said bolt including inside and outside manually operable means, said inside means 10 engaging directly with the bolt, a retracting member interposed between said outside retracting means and the bolt and connected to the bolt, and means associated with said inside retracting means adapted upon manipulation of the latter in a direction reverse to its bolt-retracting direction to remove said retracting member from operative relation with said outside retracting means.
4. In a latch, a latch bolt, retracting means 20 for said bolt including inside and outside manually operable means, a retracting member interposed between said outside retracting means and said bolt, said inside retracting means including means operatively related to said retracting member, whereby movement of said inside retracting means in one direction is adapted to retract the bolt and in the other direction is adapted to remove said retracting member from operative 25 relation with the outside retracting means.
5. In a latch, a latch bolt, retracting means for said bolt including inside and outside manually operable means, a retracting member interposed between said outside retracting 30 means and the bolt and hingedly connected to said bolt, and means associated with said inside retracting means adapted upon manipulation of the latter in a non-bolt-retracting direction to remove said retracting member from operative relation with said outside retracting means.
6. In a latch, a latch bolt, retracting means for said bolt including inside and outside manually operable means, a retracting member interposed between said outside retracting 45 means and the bolt, connected to the bolt, and normally disposed in the path of movement of said outside retracting means, and means associated with said inside retracting means adapted upon manipulation in a non-bolt-retracting direction to remove said retracting member from the path of movement of said outside retracting means.
7. In a latch, a latch bolt, retracting means for said bolt including inside and outside 50 manually operable means, a retracting member interposed between said outside retracting means and the bolt and connected to the bolt, a lever associated with said inside retracting means adapted upon manipulation 55 of the latter in a non-bolt-retracting direction to remove said retracting member from operative relation with said outside retracting means.
8. In a latch, a latch bolt, retracting means 60 for said bolt including inside and outside manually operable means, a retracting member interposed between said outside retracting means and the bolt and movably connected to the bolt, a lever disposed in relation to said inside retracting means, and cam means carried by said inside retracting 65 means adapted upon manipulation of the latter in a non-bolt-retracting direction to move said lever whereby the latter is adapted to remove said retracting member from operative relation with said outside retracting 70 means.

Signed at Bridgeport, in the county of Fairfield, and State of Connecticut, this 4th 75 day of May, 1926.

RAYMOND G. MOORE.
